ULRICH DIEM-BERNET, OF SPEICHER, SWITZERLAND

DEVICE FOR DISPLAYING ADVERTISEMENTS UNITED IN A STRIP

Application filed September 26, 1932, Serial No. 634,965, and in Switzerland October 14, 1931.

This invention relates to devices for displaying advertisements that are united in a strip, wherein a series of pictures is moved past a viewing aperture, provided in a casing, in the form of a strip which is passed over two driven winding rollers and alternatively wound on one or the other roller or unwound therefrom respectively. A change-over device for changing the direction of movement of the strip is included in the device.

Devices of this type are adapted to be mounted at any suitable place and are required to run for a greater number of days in altogether dependable manner without attendance. For this purpose, with the device according to the invention at least one driving motor is associated and a driving gearing is provided between the driving motor and the winding rollers which gearing comprises a shiftable coupling on each axle of the winding rollers as well as means that are positively responsive to a change of direction of rotation for automatically connecting one of the couplings, when the picture strip is completely unwound, and simultaneously disconnecting the other coupling and conversely, while for effecting the change of direction of movement of the picture strip each winding roller is associated with a part cooperating therewith which is urged in an inner position by the wound on strip portions and after the complete unwinding of the strip is moved outwardly, thereby displacing a driving member which on further rotation of the roller actuates means for changing the direction of movement of the strip.

In the accompanying drawings a constructional form of the invention in which a single reversible electro-motor is employed for driving the winding rollers is shown, in which

Fig. 1 shows a front elevation of the device with opened doors;

Fig. 2 is a vertical section on the line II-II in Fig. 1 showing the picture strip to be illuminated by directly incident light rays;

Figs. 3, 4 and 5 show views of details of the driving gearing;

Fig. 6 is a view of a detail of a reversing means for the motor;

Figs. 7 and 8 show an elevation and a longitudinal part section respectively of a winding roller, on a larger scale;

Fig. 9 is a section on the line IX-IX in Fig. 8;

Fig. 10 is a section on the line X-X in Fig. 8.

Fig. 11 is a section similar to Fig. 10 of the winding roller with parts in different positions;

Figs. 12 to 15 are views of details of the connections of individual foils to the picture strip.

Referring to the drawings, the device as illustrated is provided with a supporting structure in the form of a rectangular frame 1 which is closed in front by a door 2, hinged thereto and comprising a viewing aperture 3, and at the back by a door 4 also hingedly connected to the frame. Laterally on the frame 1 two casings 5 and 6 are provided which are adapted to be closed in a similar manner as the frame by means of doors 7 and 8 respectively. Inside the frame two winding rollers 9 and 10 are rotatably mounted, one above the other, for winding the picture strip 11 alternately on or off the rollers. The picture strip runs over guide rollers 12 and a guide disposed behind the viewing aperture, but not shown in the drawings. In order to permit displaying the foils, containing the advertising matter and constituting the picture strip, by transparent light, in the back door 4 strip light lamps 13 are arranged. Behind the door 4 adjacent the lamps, a reflecting wall 13' is positioned.

For driving the winding rollers 9, 10, in the casing 5 a reversible electromotor 14 is housed with which a reduction gearing 15 is combined. The shaft 16 of the reduction gearing carries a bevel gear wheel 17 which is in mesh with a bevel gear 18 on a stub shaft 19 mounted in the frame 1. To the latter a screw wheel 20 and a chain wheel 21 are fixed (Figs. 1 and 4). With the screw wheel 20 a screw wheel 22 cooperates which is rigid

with an axially displaceable claw clutch portion 23, the other portion 24 of this clutch being secured to the axle 25 of the upper winding roller 9. In similar manner, as shown in Fig. 5, on the axle 26 of the lower winding drum 10 a portion 27 of a claw clutch is secured and the counter portion 28 of this clutch displaceably arranged on this axle and provided with a screw wheel 29 rigidly connected thereto. In mesh with the screw wheel 29 is another screw wheel 30 which is connected to a stub shaft 31 carrying a chain wheel 32 cooperating with the chain wheel 21 through the intermediary of a chain 33 (Fig. 3). The inclination of the gear teeth of the cooperating screw wheels of the driving gear portion for the upper shaft (Fig. 4) is opposite to that of the screw wheels for driving gear portion of the lower shaft (Fig. 5). With this arrangement is attained that during the change of direction of rotation of the driving motor, in consequence of the axial thrust, the two claw clutches are connected or disconnected respectively, and particularly suchwise, that every time the winding roller on which the picture strip is wound is driven by the motor, whereas the coupling of the other winding roller is disconnected. Suitably the winding roller from which the picture strip is unwound is slightly braked by any known means not shown.

The reversing of the motor is effected by reversing the exciting winding thereof by means of a switch 34 (Fig. 1) provided for this purpose which is operable by a lever 35. The operation of the switch 34 sets in at the moment, when the picture strip is completely unwound from the respective roller, as follows: As shown in the Figs. 9 to 11, a portion 36 of the barrel 37 of the winding rollers 9, 10 is constructed as a flap pivotally connected to the roller at 38. To the inner side of the barrel portion 36 an inwardly projecting member 39 is screwed which carries a circumferentially directed extension 40 which abuts against the barrel, when the flap is swung outwardly, as indicated in Fig. 11. The member 39 cooperates with one arm 41 of a bell crank lever which is acted upon by a spring 42 which tends to push the arm 41 outwardly into a position, as shown in chain dotted lines in Fig. 8, thereby swinging the flap 36 outwardly. To the other arm 40 of the bell crank lever a rod 44 is linked which is passed with its outer end through the flange 45 of the winding roller to provide a driving member for a loosely mounted rotatable segment 46. Over the segment 46 of the upper winding roller and the segment 47 of the lower winding drum flexible tension members 48, 49 respectively are passed both tension members being connected to a buckle 50 (Fig. 6) which is linked to the end of the switch operating lever 35.

The flap 36 is pressed inwardly by action of the wound on portions of the picture strip (Fig. 10), whereby the rod 44 is retracted from the path of movement of the segment 46. As soon as the picture strip is unwound from the respective winding roller to such an extent that the flap 36 is layed bare, the latter is urged outwardly by action of the spring 42, so that the end of the rod 44 projects beyond the respective face of the correlated winding roller. While the latter continues its rotation the end of the rod hits the segment 46, as shown in Fig. 9, to the effect of turning the same, thus exerting tension on the buckle 50, by means of the tension member 48, and consequently displacing the lever 35 and thereby shifting the switch 34, so that the motor by changing its polarity is caused to turn in the opposite direction. At the same time, due to the different directions of inclination of the gear teeth of the screw wheels 29 and 30, the previously operative claw clutch 23, 24 is put out and the previously ineffective claw clutch 27, 28 is put in and incidentally the winding roller from which the picture strip was unwound turns in the opposite direction for winding on the picture strip. The reversing of the motor and of the driving gearing for actuating the other winding roller is effected entirely automatically as soon as the picture strip is completely unwound from the respective roller.

Fuses 51 are included in the motor circuit, as shown in Fig. 1. For avoiding undue heating up of the picture strip the upper and lower walls of the frame 1 are provided with ventilating openings 52. The lamps 13 are so far set back from the plane of the door 4 that the main part of the heat produced can escape upwardly. Apertures 54 in the door contribute to enlivening the circulation of the heated air.

The picture strip 11 consists of individual foils 55 which are suitably so connected to each other that the ends of the foils are permitted of shifting in the direction of movement as well as perpendicularly thereto. This arrangement provides for completely compensating the displacements accruing from fluctuations in the tensile stressing of the material during the on and off winding periods and the variations of the radii of curvature of the wound on layers of the strip. For this purpose the edges of the foils extending transversely to their direction of movement are inserted in clamping rails or bars consisting of thin steel bands longitudinally folded in such manner that two portions 56, 57 bent down on each other are formed (Fig. 14). The ends of the rails are provided with notches 58 engaged by clamps 59 constituted by two eyelets pivotally connected by means of a hinge 60. The eyelets are slid on the ends of the rails, as indicated in Fig. 13, and then inserted in the notches.

Each rail is free to shift in the eyelet for at least the depth of the notch in the direction of movement, and also relative shifting of adjacent rails transversely to the direction

5 of movement is readily afforded the eyelets being adapted to assume an inclined position on the rails. Furthermore, the hinges 60 permit of the joint adapting itself to the curvatures necessary for the various layers.

10 In Fig. 14 the relative thicknesses of the rails and clamps are shown in exaggerated manner, in reality these parts are scarcely thicker than the foils of the picture strip, thus increasing the overall dimensions of the round

15 wound on layers but very little. The fastening of the first and last foils of the picture strip to the respective winding rollers is effected in similar manner. To this end eyelets 59' (Fig. 7) are arranged at the end of 20 a thin metal band 61 secured to the winding roller and the ends of the rails inserted in the eyelets 59'.

In order to avoid an undesirable disengagement of the eyelets with the notches 58, 25 in the stead of the latter apertures 58', as shown in Fig. 15, may be provided. To the same effect the eyelets or nooses may be arranged to grasp the rails by inherent spring action thus sticking to their positions. When 30 the picture strips are comparatively wide, in addition to the two exterior clamps 59 a further clamp may be arranged in the middle longitudinally of the rails 56, 57. This middle clamp may be formed by two pivotally connected flat hooks for engaging in rectangular openings in the rails. Alternatively 35 a fabric band may be passed through aper- ture of adjacent rails. On the other hand several notches may be provided in each end 40 portion of the rails so as to permit of displaying picture strips of different widths with the same device. Thereby with narrower foils the clamps are inserted in the interior notches and with wider foils in the 45 exterior notches with a view to interconnect the rails as close to the lateral edges of the foils as possible.

The rails may be provided with any suitable cross section; for foils in the form of 50 posters, for example, a half round profile may be employed in order to provide the necessary rigidity.

The edges of the foils to be inserted in the rails may also be folded over, moreover, in 55 the thus formed folded seam an insert made of any suitable material may be placed so as to provide for a better clamping action of the rails.

This type of connection for the foils permits of exchanging any foils or all the foils 60 of the strip in a convenient and quick manner. By simply compressing the folded portions of the rails the edge of the foil is firmly and unmovably held. The foils may be connected to the rails along the full length of the

latter or only at the ends thereof so as to provide for free adaptation of the edges of the foils to expansions or contractions that may arise in the foil material.

As material for the picture foils any flexible transparent foil material inclusive of woven fabrics may be used. Suitably a thin non-inflammable cellulose film is used which may be of a glass-clear transparency or of a translucency similar to frosted glass and to which the advertising matter is applied by any suitable graphical or photographic reproduction method.

Alternatively the material may consist of paper having a uniform structure which is subsequently made translucent by treatment with any substance for producing this effect, for example a suitable varnish or oil. After the drying of this substance a coating of a substance having a resistance against heat and humidity such as a cellulose lacquer may be applied to the material in such a manner that the material is completely enclosed in the coat in a moisture and heat proof manner. In this way foils permanently true to form are obtained which besides do not stick together. Eventually the foils may be coated with talcum. When particularly efficacious diaphane pictures are to be obtained repeated printing may be applied to the foils or a greater amount of printing colours. By so choosing the foil material and the connecting means therefor a very considerable number of individual foils united in a picture strip may be displayed by means of a relatively small device.

In the above-described constructional form of the invention both winding rollers are actuated by one and the same driving motor 105 the motor and the driving gearing being disposed at the side of the picture strip.

I do not limit myself to the particular size, shape, number or arrangement of parts as shown and described all of which may 110 be varied without going beyond the scope of my invention, as shown, described and claimed.

What I claim is:

1. In a device for displaying advertisements united in at least one strip, in combination a housing for the device comprising a viewing aperture, a single driving motor mounted in said housing, switching means for reversing said motor, two winding rollers for winding the strip on or off respectively, a movable part of each winding roller controlled by engagement of portions of the strip wound on the respective roller, two disconnectable clutches one each intercalated 115 between said driving motor and one of said winding rollers, two screw wheels having oppositely inclined gear teeth one each connected to the movable part of one of said disconnectable clutches, counter screw wheels 120

- driven from said single motor meshing with said screw wheels and adapted for automatically disconnecting one of said clutches upon the complete unwinding of the strip from its correlated winding roller and for connecting the clutch correlated to the other winding roller by action of the axial thrust of the engaging gear teeth, and an actuating means for said switching means associated with each winding roller adapted to reverse said motor on disengagement of the strip portions unwinding from the respective winding roller with the movable part of this same winding roller.
- 15 2. In a device for displaying advertisements united in at least one strip, in combination, a housing for the device, comprising a viewing aperture, at least one driving motor mounted in said housing, switching means for reversing said motor, two winding rollers for winding the strip on or off respectively, a movable part of each winding roller controlled by engagement of portions of the strip wound on the respective roller and linked to the fixed part of the respective winding roller, a spring associated with each of said movable parts for urging the same outwardly, a bell crank lever for each winding roller controlled by the movable part of the respective roller, two disconnectable clutches one each intercalated between said driving motor and one of said winding rollers, means responsive to a change of direction of rotation inserted in the drive of said winding rollers for automatically disconnecting one of said clutches upon the complete unwinding of the strip from its correlated winding roller and for connecting the clutch correlated to the other winding roller, and an actuating rod for each winding roller linked to the related bell crank lever and passed with its other end through the respective end face of the roller, a segment loosely mounted on each winding roller adjacent said end face and cooperating with the end of said actuating rod projecting from said face, and two tension members one each interconnecting one of said segments with said switching means for reversing said motor.
- 20 4. A picture strip for advertising display purposes, comprising a series of picture foils constituting the strip, metal rails for interconnecting adjacent foils and foldable metallic connecting means slid on the ends of the rails of adjacent foils and adapted to displace themselves lengthwise of the rails for yieldingly connecting said rails to each other in the longitudinal and transverse direction of the strip and adapted to maintain said rails parallel to each other.
- 25 5. In a picture strip for advertising display purposes, a series of picture foils constituting the strip, metal rails for interconnecting adjacent foils and longitudinally folded for clampingly receiving the edge of a foil, notched ends of said rails, and clamps composed of two pivotally connected portions engaging in the notched ends of the rails of adjacent foils for yieldingly connecting the rails in the longitudinal and transverse direction of the strip to each other and permitting the clamps to adapt themselves to the respective curvatures when the strip is wound in a coil.
- 30 In testimony whereof I have signed my name to this specification.
- 35 6. In a device for displaying advertisements united in at least one strip, in combination, a housing for the device comprising a viewing aperture, at least one driving motor mounted in said housing, switching means for reversing said motor, two winding rollers for winding the strip on or off respectively, a movable part of each winding roller controlled by engagement of portions of the strip wound on the respective roller and linked to the fixed part of the respective winding roller, a spring associated with each of said movable parts for urging the same outwardly, a bell crank lever for each winding roller controlled by the movable part of the respective roller, two disconnectable clutches one each intercalated between said driving motor and
